UNITED STATES PATENT OFFICE.

BYERS W. KADEL, OF BALTIMORE, MARYLAND, ASSIGNOR TO THE T. H. SYMINGTON COMPANY, OF NEW YORK, N. Y., A CORPORATION OF DELAWARE.

DRAFT RIGGING.

Application filed July 24, 1920. Serial No. 398,729.

To all whom it may concern:

Be it known that I, BYERS W. KADEL, a citizen of the United States, residing at Baltimore, in the State of Maryland, have invented certain new and useful Improvements in Draft Rigging; and I do hereby declare the following to be a full, clear, and exact description of the invention, such as will enable others skilled in the art to which it appertains to make and use the same.

The invention relates to railway cars, and more particularly to draft rigging therefor, and the primary object of the invention is to provide a simple, strong and reliable means for connecting the cushioning elements to car couplers.

The invention moreover consists in improvements in the parts and devices and in the novel combination thereof as hereinafter described and claimed.

Referring now to the drawings, wherein I have shown a single embodiment of the invention,—

Figure 1 is a plan view, partially in section, illustrating a draft rigging embodying my invention and the adjacent portions of the car underframe.

Fig. 2 is a side elevation partially in section of the structure illustrated in Fig. 1, the section being taken adjacent the inner face of one of the center sills.

Throughout the specification and drawings like parts are designated by like reference characters.

The center or draft sills of the car are designated by the reference numeral 1, and to the outer faces thereof is connected a conventional form of cheek-plates or stop castings 2 each of which is provided with an elongated front slot 3 and a second elongated slot 4. It will be of course understood that the sills 1 are correspondingly slotted and the cheek castings 2 are preferably provided with bosses 5 which extend into the slots in the sills, as clearly shown in Fig. 1.

The coupler stem 6 is provided with a transversely extending slot through which the key 7 is adapted to extend, the said key extending outwardly from the coupler through the slots in the sills and through the slots 3 in the cheek-plates 2. In rear of the coupler, and normally contacting the same, is the front follower block 8 which is

maintained in position by means of the transversely extending key 9, said key normally 55 engaging the forward ends of the slots 4 in the said cheek-plates. In rear of the follower 8 and interposed between the same and the rigid back stop 10 is the cushioning unit 11 which preferably comprises a rectangular 60 casing 12, a cylindrical barrel 13, friction blocks 14 adapted normally to contact the internal surface of the barrel 13, and a wedge or spreader block 15. It will of course be understood that some form of spring mechanism 65 is seated within the rectangular casing 12 of the barrel and acts as a cushion against the inward movement of the friction blocks and wedge 14 and 15, respectively.

To operatively connect the coupler to the 70 cushioning mechanism I provide a pair of link or yoke members 16 each of which comprises a loop member 17 adapted to extend around and normally contact the rear face of the rectangular casing 12, and a forward 75 extension 18 in which I provide the slots 19 and 20. Each of the said slots is preferably elongated to permit the rearward movements of the keys 9 and 7 which extend through the respective slots. Adjacent their forward 80 ends the portions 18 of the said members may be provided with enlargements 21 which increase the bearing area against the forward edge of the key 7. A carry iron, such as 22, may be provided, the carry iron being 85 adapted to extend under and form a support for the members 16 and the cushioning unit 11, said carry iron being connected to the lower flanges 23 of the sills 1 by means of bolts 24.

While it is believed that the operation of the device will be clear to those skilled in the art, it might be stated that on an inward movement of the coupler the cushioning element 11 is held from movement by its contact with the stop casting 10, the latter being rigidly connected to the inner faces of the sills in a conventional manner. The links 16 are held from rearward movement by the contact with the forward face of 100 the rectangular casing 12 and the follower block is forced rearwardly, pressing the cushioning unit within the casing 12 by forcing the wedge and friction blocks within the said casing. This movement continues 105 until the keys 7 and 9 are arrested by

contact with the ends of the respective slots 3 and 4, and when the coupler 6 is relieved from strain the parts return to their normal position illustrated in Fig. 1. On 5 the outward movement of the coupler the links 16 draw the casing 12 forwardly over the wedge and friction blocks the forward movement of which is arrested by the front follower 8 which is held stationary by reason 10 of the engagement of the forward edges of the key 9 with the forward ends of the slots 4.

It will be observed that by forming the links with a loop member I am enabled to 15 utilize the width or space between the inner faces of the sills. This construction is particularly advantageous in cases where the width of the sills prevents the use of a horizontal yoke which necessitates the friction 20 casing being located with its greatest width in a vertical direction, and at the same time avoids the necessity of using a vertical yoke with a hooded forward end. The link members being located at the sides of the coupler 25 may be connected directly thereto by the transversely extending key and the strains imposed upon the link members are carried in a direct line with the consequent advantages. By locating the links on opposite 30 sides of the center of the casing 12 it is possible to employ a rigid back stop which bridges the space between the sills and acts as a tie to prevent the spreading thereof. By providing the link members with loop 35 portions I eliminate the use of a key follower at the rear of the gear and hence materially shorten the over all length and at the same time avoid the necessity of sharp angular changes adjacent the rear end 40 of the casing which are embodied in a horizontal yoke.

Having now described my invention, what

I claim and desire to secure by Letters Patent is:—

1. In a draft rigging, the combination 45 with a pair of draft sills, of a coupler, a cushioning mechanism therefor, said mechanism including a casing, a stop member connected to said sills and adapted normally to engage the inner face of said casing, a follower interposed between said coupler and cushioning mechanism, and means for operatively connecting said coupler, follower and casing, said means comprising a pair of relatively thin spaced counterpart 50 forged steel members slidably connected to said coupler and follower, and each having a portion adapted to surround the said casing.

2. In a draft rigging, the combination 60 with spaced draft sills, of a coupler, a cushioning mechanism therefor, said mechanism including a casing, a slotted follower, a stop member bridging the space between said sills and connected to the same and 65 adapted normally to engage the said casing, and means for operatively connecting said coupler and casing, said means comprising a pair of spaced counterpart members 70 slidably connected to said coupler and each adapted to partially enclose the said casing, the inner ends of said members engaging the said casing on opposite sides of the said stop member, and a key passing through the said follower and adapted to connect the 75 said members thereto.

3. A forged steel yoke for draft rigging comprising a pair of relatively flat counterpart members each of which comprises a 80 loop portion and an extension, said extension being provided with a plurality of alined elongated slots.

In testimony whereof I affix my signature.
B. W. KADEL.
